[57] CLAIM

The ornamental design for a combined post and mail box, as shown and described.

DESCRIPTION

FIG. 1 is a front and left side perspective view of a combined post and mail box showing my new design; FIG. 2 is a rear and right side perspective view thereof; FIG. 3 is a front and left side perspective view thereof with the top in pivoted, raised position; and FIG. 4 is a top plan view thereof. The bottom is plain and unadorned.
